ROAD GRADING MACHINE

Kenneth W. Porter, Effingham, Ill., assignor to
 Moritz-Bennett Corporation, Effingham, Ill., a
 corporation of Illinois

Application February 23, 1932, Serial No. 594,573

16 Claims. (Cl. 37—155)

My invention relates in general to grading machines and more in particular to a grader adapted to travel on a finished road surface and perform an operation on the road shoulder at the side thereof.

Those skilled in the art are referred to the prior patent of Charles J. Moritz, No. 1,672,497 disclosing the type of machine to which the invention applies.

10 The principal object of the present invention is to improve machines of this character.

Another object is to minimize the possibility of side draft when the outer end of the mold board is under a heavy load.

15 Another object is the provision of an improved wing cutter or shoulder sloper which may be adjusted under load.

Another object is the provision of an improved attachment on the mold board for cutting the shoulder to facilitate construction of the so-called "metal edge" shoulder.

20 Another object is to provide improved means for confining the movement of earth to the shoulder and prevent such earth from being deposited on the pavement.

25 Another object is the provision of means for checking and adjusting the pitch of the main mold board.

Another object is the provision of an improved 30 road edge marker utilizable by the operator to facilitate proper control of the position of the cutting blade.

Other objects and features of the invention 35 will be apparent from a consideration of the following detailed description taken with the accompanying drawings, wherein

Fig. 1 is a plan view of the improved grader of my construction;

40 Fig. 2 is a sectional view taken on the line 2—2 of Fig. 1, showing an elevational view of the pavement edge marker;

45 Fig. 3 is a side elevational view looking at the right hand side of Fig. 1, the mold board, however, being shown straight to facilitate the disclosure;

Fig. 4 is an end view, looking at the rear end of Fig. 1;

50 Fig. 5 is an enlarged view showing the wing cutter mounting means and control therefor;

Fig. 6 is an enlarged end view of the end of the mold board, the wing cutter being positioned as shown in Fig. 5;

Fig. 7 is a plan view showing the pavement edge scraper;

55 Fig. 8 is a side elevational view thereof;

Fig. 9 is an elevational view showing a mold board pitch indicator;

Fig. 10 is a plan view thereof;

Fig. 11 is an elevational view of an auxiliary scraper blade; and

Fig. 12 is a plan view thereof.

I shall first refer to the general features of the grader itself, so that the improvements therein and the manner in which they function will be more readily understood. The grader has a carriage frame 16 with the rear wheels 17 and the steerable wheels 18 controlled by a steering wheel 19. The frame has a front side extension 21, and a rear side extension 22. The front side extension comprises merely an extension of a front transverse frame member, while the rear extension 22 includes several structural members secured together with cross bracings and the like to form a rugged transverse mold board supporting extension (Fig. 4). A draw bar 23 connects the two extensions and an offset hitch arrangement 24 provides means for drawing the grader by a tractor in such a way that the greatest amount of pull will be substantially in line with the mold board 26. For adjusting the pitch and elevation of the mold board a bracket 27 is provided tiltably supported on the extension 22. The inclination of the bracket is controlled by a hand wheel 28 and the bodily vertical position of the mold board is adjusted by a hand wheel 29. In effecting this adjustment the mold board is carried on a vertical post 31 by a bottom bracket 32 and the entire post is reciprocable vertically by the action of the hand wheel 29 in the bracket 27. An operator's platform 33 is provided so that the operator will be in a position to view the work which the mold board is performing and have the adjusting means thereof within its reach at all times.

One of the improvements in the grader as now disclosed is an improved means for preventing side draft. The offset hitch together with the weight of the carriage frame are adequate to hold the grader on an even line for all usual operations. When operating on certain types of earth on the road shoulder, particularly when a large volume of earth is being moved, there is still a tendency for the carriage to shift, this tendency being toward rotation in a clockwise direction looking at Fig. 1 of the entire carriage about a virtual pivot point between the draft device 24 and the mold board. I overcome this tendency by means of a couple bar comprising a pair of telescope members 34 and 36 having a substantially universal pivot connection to the

frame and inside end of the mold board respectively. A pin 37 interconnects the two telescoping members extending through a selected pair of series of holes on the two members whereby the length of the couple bar may be adjusted depending upon the angle of inclination of the mold board to the work. The joints at the end of the couple bar permit adjustment of the mold board in any of the usual ways, as for example, the inclination secured by rotating the mold board with the post 31 as an axis, inclining its pitch or adjusting it bodily vertically by means of the hand wheel 29.

In the shoulder operations it is often customary to cut a slope on the outside edge of the shoulder. This slope usually forms one wall of a drainage ditch and the angle thereof depends upon the design of the ditch. For cutting this slope I provide a sloper or wing cutter 38 pivoted at 39 (Fig. 5) to the end of the mold board so as to be adjustable thereon. An angle bar 41 reinforces the wing cutter and has an extension bearing over against the back of the mold board whereby some of the strain is taken off of the pivot. For adjusting the slope of the wing cutter I provide trunnions 42 and 43 supported between suitable brackets carried by the mold board and wing cutter respectively of the character shown in the drawings. The trunnions are provided with right and lefthand threads and an adjusting screw 44 operated by a hand wheel 46 is threaded in the trunnions. It is clear then that by operating the hand wheel the wing cutter may be rotated around the pivot 39 to any suitable inclination within the limits of the design and will be held at such inclination by the adjusting screw 44.

In some types of shoulder work it is customary to cut a relatively narrow and shallow trench along the edge of the shoulder close to the road and fill this trench with stones and/or coarse gravel so that a solid surface will result on the shoulder immediately adjacent the hard roadway. This, of course, is a safety factor to minimize the possibility of accident if a motorist accidentally allows his outside wheels to cut over off of the pavement. In order to cut this trench I provide a cutting member 47 bolted to the inside edge of the mold board so as to be readily removable or as readily applied. As the drawings show the member 47 is shaped to have a plow action along the edge of the pavement and also an earth removing action whereby the earth loosened by the plow action is removed and eventually is spread over the remaining portion of the shoulder by the main portion of the mold board.

A member 47 includes a removable cutting edge 50 bolted to the portion thereof secured to the mold board and designed to be reversible so that either edge can be brought into position to do the cutting. The portion 47a, integral with the auxiliary member 47, extends back at an angle so that if the mold board is brought too close to the pavement there will be no possibility of the cutting blade 50 catching on the edge of the pavement and being torn loose or otherwise injured. Since the mold board is disposed at an angle, it is clear that there is a relatively wide surface of the portion 47a which can come in contact with the pavement edge. A portion 47b extends at an angle forwardly to prevent earth picked up by the plow action of the auxiliary cutter from spilling over due to its volume onto the edge of the road.

When earth is being removed by the mold board 26, there are occasions when the volume of dirt

is so great that an excess amount of dirt may work around the inner end of the mold board and be deposited onto the pavement. Usually this is no more than could readily be distributed over the shoulder, but if left on the pavement a separate operation is required to remove it or an unsatisfactory job is produced. Under such circumstances, I employ an auxiliary mold board or pavement scraper 51 mounted on the frame in back of the mold board proper and so disposed with respect to the pavement as to remove earth deposited on the pavement by the mold board and spread this earth out over the shoulder. The auxiliary mold board or pavement scraper is adjustable as to inclination and is readily removed from the frame in the event that its use is not required. 5

As Fig. 8 shows, the pavement scraper is relatively loosely carried so as to move at an angle over the road surface. There may be times when the pavement scraper is not required, however, and I therefore apply means for taking it out of contact with the road surface. The scraper itself is loosely held by the link 71, having one end connected to the scraper blade and the other end pivoted at 72 to a bell crank lever 73. This lever is pivoted at 74 between a pair of plates 76-76 and has a relatively long arm 77 with which the blade can be raised. This arm is provided with an opening 78 adapted to be brought into alignment with the corresponding opening 79 in the plates 76. When the pavement scraper is raised by pulling downwardly on the arm 77 of the bell crank, the holes 78 and 79 are lined up and the pin inserted through the holes prevents the arm from moving back due to the gravitational force of the scraper and so the pavement scraper is held out of engagement with the road surface. 30

I also provide means for controlling the pitch of the mold board. In general, it is customary to cut the shoulder so that it will constitute, as far as its surface is concerned, a continuation of the hard road surface. It may be necessary, however, to cut the slope at somewhat of an angle to the road surface for various reasons. Also, when cutting below the road surface as is done when the main road is to be widened, for example, it is necessary to control the pitch of the mold board accurately. Heretofore it has been customary to check the pitch merely with the eye, this being facilitated of course by the fact that the carriage was traveling on the road surface and furnished a very excellent guide. 50

For accomplishing my result I provide a level attachment 52 shown in Fig. 1 in its position on the mold board, and shown in Figs. 9 and 10 enlarged to facilitate the disclosure. The level attachment comprises a plate 53 having a scale 54 and carrying an adjustable arm 55 pivoted at 57. The opposite end of the arm extends under an arcuate guide 58 and a strap 59 extending over the arcuate guide 58 carries an anchoring bolt 61 for securing the arm 56 at any suitable inclination with respect to the plate 53. The arm carries a bubble type level indicator 62 and has a pointed end 56a extending up to and cooperating with the scale 54. 60

In using the device the proper pitch of the mold board is set and the arm 56 adjusted to center the bubble in the level indicator 62. The position of the pointer will then indicate the pitch of the blade, and when using the grader it is merely necessary for the operator to maintain the bubble in a center position and he knows that he is adjusted to the proper pitch. Attention is also directed to the fact that the arm pointer 56a is 70 75

a guide for determining the pitch to which the mold board is set. This makes it possible to set the mold board using a previously cut shoulder as a guide so that the same pitch of the slope is duplicated, or to set the pitch entirely in accordance with specifications calling for a certain angularity with respect to the road. In connection with this pitch adjustment, those skilled in the art will recall that road surfaces are also pitched at times either toward the center or away from the center, while at other times they are perfectly flat. When operating on different types of hard surface roads, it is obvious therefore that the pitch adjustment may become of considerable importance.

As a guide to the operator I provide a pavement edge marker comprising a U-shaped strap 64 adjustably supported along the extension 21 having a pointer 66 pivoted between the ends of a pair of supports 67, the supports themselves having their upper ends pivoted to the member 64. The depending pointer or marker 66 being pivoted can ride over obstructions and the like without injury in the direction in which the 20 grader is moving, but is immovable in a transverse direction, so that it always maintains an exact line which the operator can use as a guide in controlling the position of the grader on the pavement.

Those skilled in the art will understand how the different features of the invention cooperate to produce a unitary result. The couple bar is of particular use where a relatively greater strain is placed on the inside end of the mold board such as occurs when the auxiliary cutting blade is attached to the mold board. In this case also there is a tendency for more earth to be deposited on the road surface and the scraper is therefore of advantage in the combination. The use of the pavement edge marker is of particular advantage when the "metal edge" shoulder auxiliary cutter is employed as the shallow trench produced by this auxiliary cutter should be at the very edge of the hard road.

Although I have described the features of my invention in detail to enable those skilled in the art to practice the same, it is obvious that I do not limit myself to the specific form shown, and the invention is limited only by the scope of the appended claims.

What I claim as new and desire to protect by United States Letters Patent is:—

1. A grader having a carriage adapted to travel on a hard road surface, a side projection therefrom, a mold board adjustably supported on said side projection, and an adjustable couple bar secured by universal joints between the carriage and a point on the mold board near the end thereof closest to the hard road surface.

2. A grader having a carriage adapted to travel on a hard road surface, a side projection on the carriage, a mold board adjustably supported on the side projection, an auxiliary cutting blade narrower than the mold board secured near the inner end thereof and projecting below the mold board to cut a shallow trench below the road shoulder and adjacent the hard road, and means carried by the auxiliary cutting blade for removing earth from the edge of the hard road surface.

3. A grader having a carriage adapted to travel on a hard road surface, a side projection on the carriage, a mold board adjustably supported on the side projection, an auxiliary cutting blade narrower than the mold board secured

near the inner end thereof and projecting below the mold board to cut a shallow trench below the road shoulder and adjacent the hard road, said auxiliary cutter blade having a portion extending at an angle rearwardly thereof and adapted to bear against the hard road edge, and also having a portion extending a short distance across the surface of the hard road for removing earth deposited on the road by the auxiliary cutting blade.

4. A grader having a carriage adapted to travel on a hard road surface, a side projection on the carriage, a mold board adjustably supported on the side projection, an auxiliary cutting blade narrower than the mold board secured near the inner end thereof and projecting below the mold board to cut a shallow trench below the road shoulder and adjacent the hard road, and an adjustable couple bar secured by the universal joints between the carriage and a point on the mold board near said auxiliary cutting blade.

5. A grader having a carriage adapted to travel on a hard road surface, a side projection therefrom, a mold board adjustably supported on said side projection, a sloper cutter pivoted to the mold board at the outside end thereof, a pair of trunnions carried by the mold board and sloper, and an adjusting screw having left and righthand threads engaging with the trunnions adapted to be turned to move the sloper on its pivot for adjusting the angularity of the sloper with respect to the mold board.

6. A grader having a carriage adapted to travel on a hard road surface, a side projection therefrom, a mold board carried on the side projection and adapted to operate on the road shoulder at the side of the hard road, a frame extension projecting out over the road shoulder in advance of the mold board, and a pavement edge marker adjustable along said frame extension.

7. A grader having a carriage adapted to travel on a hard road surface, a side projection therefrom, a mold board carried on the side projection and adapted to operate on the road shoulder at the side of the hard road, a frame extension projecting out over the road shoulder in advance of the mold board, a draw bar extending from the frame extension to the mold board, and a pavement edge marker adjustable along said frame extension.

8. A grader having a carriage adapted to travel on a hard road surface, a side projection therefrom, a mold board carried on the side projection and adapted to operate on the road shoulder at the side of the hard road, a frame extension projecting out over the road shoulder in advance of the mold board, and a pavement edge marker adjustable along said frame extension, said marker comprising an upper part for connecting to said frame extension and a lower part pivoted to the upper part on a pivot parallel to the frame extension whereby the lower part is immovable laterally with respect to the upper part, but pivots longitudinally whereby it is permitted to ride over obstacles on the road shoulder or road without injury.

9. A grader having a carriage adapted to travel on a hard road surface, a side extension from said carriage, a moldboard adjustably supported on the side extension, an auxiliary cutting blade narrower than the moldboard secured near the inner end thereof having a portion projecting below the moldboard and extending forwardly

therefrom for cutting a shallow trench below the road shoulder and adjacent the hard road, and means for preventing earth from spilling onto the hard road surface.

- 5 10. A grader having a carriage adapted to travel on a hard road surface, a side projection on the carriage, a mold board adjustably supported on the side projection, an auxiliary cutting blade narrower than the mold board secured 10 near the inner end thereof and projecting below the mold board to cut a shallow trench below the road shoulder and adjacent the hard road, a buffer provided with a blunt edge adapted to bear against the hard road edge, and means for preventing earth from spilling onto the hard road 15 surface.

- 10 11. A grader having a carriage adapted to travel on a hard road surface, a side projection therefrom, a mold board adjustably supported on said side projection, an adjustable couple bar secured between the carriage and a point on the mold board near the end thereof closest to the hard road surface, and an auxiliary cutting blade narrower than the mold board secured near the inner end thereof substantially in line with the point of attachment of the adjustable couple bar to the mold board.

- 20 12. A grader having a carriage adapted to travel on a hard road surface, a mold board, means for supporting the mold board at the side thereof to cut a shoulder at the edge of the hard road surface, an auxiliary cutting blade secured to the mold board near the end thereof closest to the hard road surface, said auxiliary cutting 25 blade comprising a part removably secured directly to the mold board, and a part extending from said first mentioned part at an angle below the edge of the mold board for cutting a shallow trench below the road shoulder and adjacent the hard road surface.

- 30 13. A grader having a carriage adapted to travel on a hard road surface, a mold board, means for supporting the mold board at the side thereof to cut a shoulder at the edge of the hard road surface, an auxiliary cutting blade secured to the mold board near the end thereof, closest to the hard road surface, said auxiliary cutting 35 blade comprising a part removably secured directly to the mold board and having a portion projecting over the hard road surface for preventing spilling of earth thereon, and a part extending from said first mentioned part at an angle below the edge of the mold board for cutting a shallow trench below the road shoulder and adjacent the hard road surface.

ting a shallow trench below the road shoulder and adjacent the hard road surface.

14. A grader having a carriage adapted to travel on a hard road surface, a mold board, means for supporting the mold board at the side thereof to cut a shoulder at the edge of the hard road surface, an auxiliary cutting blade secured to the mold board near the end thereof closest to the hard road surface, said auxiliary cutting blade comprising a part removably secured directly to the mold board, and a part extending from said first mentioned part at an angle below the edge of the mold board for cutting a shallow trench below the road shoulder and adjacent the hard road surface, said second mentioned part having a portion extending rearwardly at an angle to provide a blunt edge bearing against the edge of the hard road.

15. A grader having a carriage adapted to travel on a hard road surface, a mold board, means for supporting the mold board at the side thereof to cut a shoulder at the edge of the hard road surface, an auxiliary cutting blade secured to the mold board near the end thereof closest to the hard road surface, said auxiliary cutting 20 blade comprising a part removably secured directly to the mold board and having a portion projecting over the hard road surface for preventing spilling of earth thereon, and a part extending from said first mentioned part at an angle below the edge of the mold board for cutting a shallow trench below the road shoulder and adjacent the hard road surface, said second mentioned part having a portion extending rearwardly at an angle to provide a blunt edge bearing against the edge of the hard road.

16. In a road shoulder grading machine having a carriage adapted to travel on a hard road surface, an extension extending outwardly from the carriage over the shoulder of the road, a mold board adjustably supported by the extension, a slope cutter pivoted to the moldboard at the outside end thereof, and means for adjusting the slope with respect to the mold board, said means including a pair of brackets extending upwardly 40 from the moldboard and slope respectively and rigidly secured adjacent adjoining ends of the same, a trunnion movably carried at the top of each bracket and an adjusting screw having left and right hand threads engaging with the trunnions to move the brackets and adjust the angularity of the slope.

KENNETH W. PORTER.
